[57] CLAIM

The ornamental design for a toilet seat handle, as shown and described.

DESCRIPTION

FIG. 1 is an upper axonometric view of a toilet seat handle showing my new design;
FIG. 2 is a lower axonometric view thereof;
FIG. 3 is a top plan view thereof;
FIG. 4 is a bottom plan view thereof;
FIG. 5 is a front elevational view thereof;
FIG. 6 is a rear elevational view thereof;
FIG. 7 is a left side elevational view thereof, the right side elevational view being a mirror image thereof;
FIG. 8 is an upper axonometric view of a second embodiment of a toilet seat handle showing my new design;
FIG. 9 is a lower axonometric view thereof;
FIG. 10 is a top plan view thereof;
FIG. 11 is a bottom plan view thereof;
FIG. 12 is a front elevational view thereof;
FIG. 13 is a rear elevational view thereof;
FIG. 14 is a left side elevational view thereof, the right side elevational view being a mirror image thereof;
FIG. 15 is an upper axonometric view of a third embodiment of a toilet seat handle showing my new design;
FIG. 16 is a lower axonometric view thereof;
FIG. 17 is a top plan view thereof;
FIG. 18 is a bottom plan view thereof;
FIG. 19 is a front elevational view thereof;
FIG. 20 is a rear elevational view thereof; and,
FIG. 21 is a left side elevational view thereof, the right side elevational view being a mirror image thereof.
